COOLING APPARATUS

John F. Plummer, Jr., Phillipsburg, N. J., assignor
to Ingersoll-Rand Company, New York, N. Y., a
corporation of New Jersey

Application July 8, 1944, Serial No. 543,983

7 Claims. (Cl. 62—152)

1

This invention relates to cooling devices, and more particularly to apparatus for the evaporative cooling of liquids, such as distillers' mash and the like, which have a marked tendency to foam during the cooling process.

One object of the invention is to effect the rapid cooling of the liquid.

Another object is to utilize the liquid being cooled as a sealing medium between successive stages of cooling.

A further object is to entirely dissipate any foam which forms during the cooling process and avoid collecting it in the liquid during its passage through the cooling apparatus.

Other objects will be in part obvious and in part pointed out hereinafter.

In the drawings accompanying this specification and in which similar reference numerals refer to similar parts,

Figure 1 is an elevation, partly broken away, of a cooling apparatus and its controlling devices constructed and arranged in accordance with the practice of the invention.

Figure 2 is a transverse view taken through Figure 1 on the line 2—2.

Figure 3 is an elevation, partly broken away, of a detail illustrating the manner in which the liquid is projected through the cooling chambers whenever the cooling apparatus is operating at or near full capacity.

Figure 4 is a transverse view taken through Figure 3 on the line 4—4.

Figure 5 is a view similar to Figure 3 illustrating the course and the stream pattern of the fluid within the cooling chambers whenever the cooling apparatus is operating at reduced capacity, and

Figure 6 is a transverse view taken through Figure 5 on the line 6—6.

Referring more particularly to the drawings, the cooling apparatus, designated in its entirety by 20, comprises a main cooling unit 21 and evacuating means, designated broadly 22, for creating the required absolute pressures in certain zones of the main cooling unit for reducing the temperature of liquid by evaporation.

The cooling unit 21 comprises an elongated casing 23 that is arranged in a vertical position so that the liquid will flow therethrough by gravity. Liquid intended to be cooled is conveyed from a source of supply (not shown) by a supply conduit 24 extending into the upper portion of the casing and having a nozzle 25 that depends axially into the casing. At the lower end of the casing is an outlet 26 that opens into a discharge

2

conduit 27 having a pump 28 arranged therein for pumping the liquid from the cooling unit.

In the form of the invention shown, the interior of the casing 23 is arranged for three stages of cooling. It accordingly has a primary cooling chamber 29 at its upper end, a secondary cooling chamber 30 below the primary chamber, and at the lower end a final stage cooling chamber 31 which communicates with the discharge conduit 10 27 through the outlet 26.

The partitions 32 and 33 separating the cooling chambers are of funnel shape. Their marginal portions 34 engage the inner surface of the casing 23 and may be connected thereto in sealing relationship in any suitable manner. The nozzle 35 depending from the axial portion of each partition has a restricted portion 36 at its outlet end to at all times assure a sufficient depth of liquid in the nozzles for sealing one chamber from the other. The outlet end portion 37 of the nozzle 25 is likewise restricted to reduce the flow area of that portion of the nozzle 25 below that of the conduit 24 and thus create the velocity required to distribute the liquid in the desired form.

Means are provided to deflect the liquid issuing from the nozzles 25 and 35 and to direct it laterally through the cooling chambers in the form of thin sheets presenting large surface areas 30 for the liberation of vapor. To this end deflectors 38 in the form of disks are disposed in front of the outlet ends of the nozzles in suitably spaced relation therewith so that the liquid entering the chambers will impinge against the deflectors 35 38 and flow smoothly across them with a minimum loss of velocity in order to form thin sheets or curtains of liquid having a high ratio of surface area to film thickness.

The deflectors 38 are supported by the nozzles. They are secured to these parts by a group 40 of baffles 39, preferably three in number, that may be fastened to the deflectors and to the nozzles in any well known manner, as for example by welding. The baffles 39 extend from the nozzles 45 radially to the marginal portions of the deflectors and they are of substantially V-shape to cause the formation of similarly shaped gaps in the curtain of liquid flowing from the deflector toward the wall of the casing. In this way are 50 provided openings in the liquid through which vapor released from the underside of the several sheets may pass into the upper zones of the chambers for removal by the evacuating means.

Normally, when operating at full capacity the 55 velocity of the liquid flowing across the deflectors

and radially through the chambers is sufficiently high to carry it to the wall of the casing whereby it will be deflected in a downwardly direction, in a manner indicated at 40 in Figure 3 of the drawings, with a minimum degree of turbulence and splashing and, therefore, with a minimum tendency to create bubbles and foam in the streams. The liquid will then flow downwardly along the wall of the casing onto and across the adjacent partition and then pass through the associated nozzle into the next chamber.

At part load operation, on the other hand, the velocity of the liquid across the deflectors and through the chambers will, of course, be less and the sheets would then tend to drop directly upon low portions of the partitions and create bubbles that might be carried into the evacuating means. This would be highly objectionable, and in order to avoid its occurrence each chamber is provided with an additional deflector 41 located between the deflectors 38 and the partitions separating the chambers.

The deflectors 41 are of frusto-conical shape. Their bases are of smaller diameter than the casing to permit the free flow of liquid between the two and seat upon racks 42 constructed of a plurality of radially extending arms, the outer ends of which may be fastened to the casing in any suitable manner. In the upper ends of the deflectors 41 are openings 43 through which vapor that might be released from the liquid flowing across the partitions may pass into the upper portions of the cooling chambers.

In the form shown, the evacuating means 22 comprises a condenser 44 of the barometric type that communicates with the chamber 29 through a conduit 45 attached to a connection 46 at the upper end of the chamber 29 so that the vapor released from the liquid in said chamber may pass directly through the conduit 45 into the condenser 44. The chambers 30 and 31 are evacuated, respectively, by steam jet boosters 47 and 48 that discharge through the conduit 45 to the condenser.

The booster 47 communicates with the chamber 30 through a conduit 49 connected to the upper end of such chamber. In like manner, the booster 48 communicates with the upper end of the chamber 31 through a conduit 50, and the steam for operating the boosters is conveyed thereto by a supply conduit 51 connected to the booster 48 and having a branch line 52 extending to the booster 47.

To the end that the desired vapor pressures may be maintained in the chambers 30 and 31 the vapor outlet conduits 49 and 50 are each provided with a damper 53, of the oscillatory plate type, connected by appropriate linkage 54 to a pressure responsive actuator 55 whereby the damper is shifted to its controlling positions. The actuator 55 may be of a well known type and the pressure serving to operate it is conveyed thereto by a conduit 56 connected at one end to the actuator 55 and at its other end to the casing 23 for communication with the associated cooling chamber. The dampers and their actuating devices are so arranged and operate in such manner that upon an increase of pressure in the cooling chambers the dampers will be shifted to positions to increase the flow area around them and, conversely, when the pressure in the chambers falls the actuator 55 acting in response thereto will shift the damper to decrease the area of communication between the cooling chambers and the boosters.

In addition to such means as may be provided for manually controlling the flow of cooling water to the condenser 44 through the supply conduit 57 said conduit is provided with a valve 58 of the poppet type having a stem 59 extending exteriorly of the conduit for connection to a temperature actuated controller 60, of a well known type. The controller 60 has the usual tube 61 terminating at its lower end in a bulb 62 containing an expansible medium, as for example mercury. The tube 61 extends into the chamber 29 across the upper surface of the partition 32 and its bulb 62 lies within the nozzle 35 of said partition so that it will be in position for intimate contact with the liquid passing through the nozzle. In this way the pressure of the mercury for actuating the controller 60 may vary in quick response to variations in the temperature of the liquid passing from the chamber 29 to the chamber 30.

By reason of this arrangement the valve 58 will be actuated for increasing the flow of water through the conduit 57 into the condenser 44 if the temperature of the liquid passing from the first stage of cooling exceeds that which it is intended to maintain, and whenever the temperature of the liquid flowing over the bulb 62 falls below the predetermined value the actuator 60 will shift the valve 58 to decrease the flow of water into the condenser.

The steam supply conduit 51 is also provided with a poppet valve 63 and a temperature actuated controller 64 for actuating it to shut-off the steam supply to the boosters whenever the temperature of the liquid in the cooling chamber 31 reaches a value at which the creation of foam might take place. The tube 65 of the controller 64 extends into the lowermost portion of the chamber 31 so that its bulb 66 will be immersed in the liquid therein.

The liquid in the chamber 31 is maintained at a suitable level to assure immersion of the bulb 66 and also to maintain a suitable suction head for the pump 28, in order to avoid cavitation therein, by a poppet valve 67 arranged in the discharge conduit 68 of the pump. The stem 69 of the valve 67 projecting from the discharge conduit has its free end pivotally connected to an end of a rocker 70 that is pivotally connected, intermediate its ends, to a casing 71 shown overlying the discharge conduit 68 between the valve 67 and the pump 28. The interior of the casing 71 constitutes a float chamber 72 and is in communication with the lower end of the cooling chamber 31 through a conduit 73 to permit the free passage of liquid from the chamber 31 into the float chamber 72 in order to maintain the same level of liquid in the float chamber that exists in the chamber 31.

One arm of the rocker 70 lies within the float chamber 72 and carries a bulb 74 that rises and falls with the liquid in the float chamber and thereby imparts movement to the valve 67 for controlling the flow of liquid through the discharge pipe 68. A conduit 75 affords communication between the upper portion of the chamber 72 and the chamber 31 to assure the same pressure upon the liquid in the float chamber 72 as that in the chamber 31.

In cooling certain hot liquids by evaporation in a high vacuum, it is of extreme importance to guard against the accumulation of a considerable body of liquid at any point in the cooling apparatus. This is particularly true to distillers' mash which foams profusely when exposed to a sudden rise in temperature or an abrupt drop in pres-

sure and it is, therefore, desirable that whenever these unfavorable conditions occur the admission of liquid into the cooling apparatus to be promptly cut-off, otherwise foam may be carried into the evacuating devices and to the liquid removal pump and cause the latter to become vapor-bound. In furtherance of this end the liquid supply conduit 24 is provided with a control valve mechanism comprising a casing 76 that is interposed in said conduit and houses a valve 77 of the poppet type. The valve 77 is urged towards its closed position by a spring 78, and on its stem 79 is a piston 80 having an actuating surface 81 at its juncture with the stem subjected to pressure fluid for opening the valve 77 to maintain a suitable flow area through the casing 76.

The pressure fluid serving to actuate the valve 77 is conveyed to the casing 76 by a pipe 82 connected to the casing 76 at a point between the valve 77 and the piston 80, and the flow of pressure fluid through the pipe 82 is metered by an orifice plate 83 in said pipe.

In order to effect the quick release of pressure fluid acting against the surface 81 in the event that the temperature of the liquid in the lower-most cooling chamber 31 rises to a dangerous degree, the pipe 82 is provided with means that acts in response to a rising temperature in the chamber 31 for venting the portion of the pipe between the orifice plate 83 and the actuating surface 81 to the atmosphere. This pressure releasing means, designated in general by 84, comprises a valve casing 85 the interior 86 of which communicates the pipe 82, through a connection 87, with the atmosphere and is controlled by a poppet valve 88. The valve 88 is actuated by a temperature actuated controller 89 which is similar in all essential respects to those designated 60 and 64 and has a conduit 90 that opens into the tube 65 of the controller 64.

Thus, by the arrangement described, whenever the temperature within the chamber 31 rises the expandible medium within the bulb 66 will, in addition to its function previously described, open the poppet valve 88 and provide an escape for the pressure fluid between the orifice plate 83 and the actuating surface 81. In this connection, it should be understood that the flow area through the valve casing 85 is at least equal to that of the orifice in the plate 83 so that the pressure surface 81 will be fully vented to the atmosphere and the spring 78 may then return the valve 77 to its closed position and cut-off the admission of fluid into the casing 23.

Preferably, means are also provided to vent the same portion of the pipe 82 to the atmosphere in response to a rising level of liquid, or foam, in the chamber 31. To this end a second pressure releasing means 91, similar to that designated 84, is connected to the pipe above the orifice plate 83 by a connection 92, and the free end of the stem 93 of the poppet valve 94 controlling communication between the pipe 82 and the atmosphere is pivotally connected to an end of a rocker bar 95.

The rocker bar 95 is connected, as by means of a pivot pin 96, intermediate its ends to the wall 97 of a float chamber 98 on the side of the lower-most portion of the casing 23. The float chamber 98 communicates with the chamber 31 through an opening 99 and is so positioned with respect thereto that its bottom surface lies approximately in the same plane as the normal liquid level in the chamber 31. The innermost arm portion 100 of the bar 95 lies in the intermediate portion

of the chamber 31 and carries a bulb or float 101 a short distance above the liquid and against which rising liquid, or foam, may act for tilting the rocker bar 95 to unseat the valve 94.

In order to admit of ready access to the several chambers 29, 30 and 31 for the purpose of making inspections, repairs, etc., each cooling chamber is provided with a manhole 102 that is sealed by a cover 103.

The operation of the device is as follows: Let it be assumed that the condenser 44 and the boosters 47 and 48 are in operation to evacuate the chambers 29, 30 and 31, respectively, for maintaining progressively lower absolute pressures in said chambers in the order named, and that the valve 77 is held in the open position by pressure fluid acting against the actuating surface 81. Liquid will then flow through the conduit 24 against the deflector 38 in the chamber 29 and will be diverted thereby against the wall of the casing 23 when operating at full capacity or will be deflected to fall upon the deflectors 41 when operating at reduced capacity. In either case the liquid flows across and from the deflectors 38 to the next deflecting surface in the form of three thin sheets, as shown more particularly in Figures 3 to 6 inclusive of the drawings.

During its passage through the chamber 29 vapor is liberated from both the upper and the lower surfaces of the sheets and the vapor released from the undersides of the sheets passes through the gaps between the sheets of liquid to pass, along with that released on the upper sides, through the conduit 45 into the condenser 44. Upon reaching the wall of the casing 23 the sheets of liquid are deflected thereby and will then flow over the partition 32 and through its nozzle 35 into the chamber 30.

This sequence of events is repeated in the chamber 30 and again in the chamber 31 with the exceptions that in the latter chamber the cooled liquid is added to the body awaiting removal by the pump 28, and the vapors are removed from the chambers 30 and 31 by the boosters.

In passing from one cooling chamber to another, the liquid will effect a seal in each nozzle 35 and thus make it possible to maintain the desired pressure differentials in the cooling chambers.

The actuators 55 will, as has been previously explained, act in response to the fluctuations in the cooling chambers wherewith they are associated to shift the dampers for increasing or decreasing the flow area through the conduits 49 and 50 to assure the desired vapor pressures in the cooling chambers 30 and 31.

If, for any reason, the temperature of the liquid in the casing 23 is caused to rise, as when the pressure of the steam operating the boosters is of an insufficient value to maintain the required vacuum in the casing, the mercury in the bulb 66 will expand and actuate the valves 63 and 92. The valve 63 will be moved thereby to its closed position to cut-off the flow of steam to the boosters, so that if foam is created in the bottom portion of the cooling apparatus the boosters will be put out of operation before foam may be drawn into the evacuating means. The valve 63 will remain in the closed position as long as the temperature of the liquid in the chamber 31 remains high, and in this way the boosters will be prevented from acting to suddenly lower the pressure on the hot liquid in the said chamber and

thereby cause the creation of a large volume of foam.

Simultaneously with the closing of the valve 63 the valve 83 will be unseated to communicate the pipe 82 with the atmosphere. In this way the pressure acting against the surface 81 of the piston 80 will be released and the spring 78 will then act to move the valve 77 to its closed position and cut-off the further flow of hot liquid into the cooling apparatus.

In the event that the liquid level in the chamber 31 rises unduly or that foam is created and rises in said chamber before the temperature actuated controller 89 may act, such liquid or foam acting against the float 101 will raise it and cause the valve 94 to be unseated for communicating the pipe 82 with the atmosphere. The pressure normally holding the valve 77 open will then be released so that the spring 78 may act to move the valve 77 to its closed position.

As will be readily understood from the foregoing description, the liquid is delivered to the cooling chambers only in the form of thin sheets that are suitably spaced with respect to each other so that vapor may be withdrawn from the entire surface area of each sheet, and the vapor released from the undersides of the sheets of liquid may readily pass upwardly between the sheets for removal to the condensing apparatus.

Moreover, the liquid enters each chamber with such a large ratio of evaporation surface compared to the thickness of the sheet that virtually all cooling takes place and all foam created by the progressive reduction in pressure is immediately dissipated before liquid reaches the walls of the chamber or is allowed to collect in any part of the apparatus. The liquid, moreover, is gently deflected at each turning point, during its course through the cooling apparatus, in such a way as to preclude the creation of foam or vapor bubbles in the liquid that would interfere with the operation of the removal pump or the inter-stage seals.

Furthermore, the entire apparatus is so constructed and its parts are so arranged that it is nonclogging and self draining throughout and thus is well adapted for cooling any liquids such as distillers mash which may contain suspended solids.

I claim:

1. In apparatus for cooling a liquid by evaporation, comprising a casing having a cooling chamber and a discharge opening, means for creating a sufficiently low pressure in the chamber to cause the liberation of vapor from the liquid, conduit means for introducing liquid into the chamber, and deflector means lying across the outlet end of the conduit means in spaced relation therewith to cause the liquid to flow through the chamber in the form of a sheet, a divider to cause the formation of an opening in such sheet of liquid for the passage of vapor from one side to another of the sheet.

2. In apparatus for cooling a liquid by evaporation, comprising a casing having a cooling chamber and a discharge opening therefor, means for creating a sufficiently low pressure in the chamber to cause the liberation of vapor from the liquid, and a conduit for introducing liquid into the axial zone of the chamber, a plurality of dividers in the chamber adjacent the outlet end of the conduit to direct the liquid radially through the chamber in the form of a plurality of relatively spaced sheets.

3. In apparatus for cooling a liquid by evapo-

ration, comprising a casing having a cooling chamber and a discharge opening therefor, means for creating a sufficiently low pressure in the chamber to cause the liberation of vapor from the liquid, a conduit for introducing liquid into the chamber, and a disk having a flat surface lying in front of the outlet opening of the conduit to direct the liquid radially through the chamber, a divider on the disk to separate the liquid into a plurality of relatively spaced, thin sheets.

4. In apparatus for cooling a liquid, comprising a vertical casing having a plurality of chambers to receive the liquid successively for cooling it by evaporation, a conduit for transferring the liquid by gravity from one chamber to another, and means in front of the outlet opening of the conduit in spaced relation therewith to deflect the liquid radially from the conduit in the form of a sheet, a divider for causing the formation of a radially extending gap in such sheet to provide a vapor path through the liquid, and a restricted portion in the conduit to restrict the flow of liquid therethrough for maintaining a liquid seal between the chambers.

5. Apparatus for cooling liquid, comprising a vertical casing having a plurality of chambers to receive the liquid successively for cooling it by evaporation, conduit means for conveying liquid from a source of supply to the uppermost of the chambers, conduit means for transferring the liquid from one chamber to another and each conduit means having a portion of reduced flow area to restrict the flow of liquid therethrough and thereby maintain a liquid seal in the conduit means, means in front of the outlet openings of the conduit means in spaced relation therewith to deflect the liquid radially from the conduit means in the form of a plurality of relatively spaced sheets, a valve for controlling the flow of liquid through the first mentioned conduit, and a plurality of controlling means for controlling the valve, one of said means acting in response to a predetermined level and another means acting in response to a predetermined temperature of the liquid in the lowermost vacuum chamber.

6. Apparatus for cooling liquid, comprising a vertical casing having a plurality of chambers to receive liquid successively for cooling it by evaporation, partitions between the chambers, conduit means for conveying liquid from a source of supply to the uppermost of the chambers, conduit means depending from the partitions into the chambers for transferring the liquid from one chamber to another and each conduit means having a portion of reduced flow area to restrict the flow of liquid therethrough and thereby maintain a liquid seal in the conduit means, means in front of the outlet openings of the conduit means in spaced relation therewith to deflect the liquid radially from the conduit means in the form of a plurality of relatively spaced sheets, a valve for controlling the flow of liquid through the first mentioned conduit, and means operating in response to the pressures in certain of the chambers for maintaining the desired cooling ranges therein.

7. Apparatus for cooling liquid, comprising a vertical casing having a plurality of chambers to receive the liquid successively for cooling it by evaporation, conduit means for conveying liquid from a source of supply to the uppermost of the chambers, conduit means for transferring the liquid from one chamber to another and each

conduit means having a portion of reduced flow area to restrict the flow of liquid therethrough and thereby maintain a liquid seal in the conduit means, means in front of the outlet openings of the conduit means in spaced relation therewith to deflect the liquid radially from the conduit means in the form of a plurality of relatively spaced sheets, a valve for controlling the flow of liquid through the first mentioned conduit, a

5 plurality of controlling means for controlling the valve, one of said means acting in response to a predetermined level and another means acting in response to a predetermined temperature of the liquid in the lowermost vacuum chamber, and means operating in response to the pressures in certain of the chambers for maintaining the desired cooling ranges therein.

JOHN F. PLUMMER, JR.
